CABLE GUIDING DEVICE

Bror A. E. Rosengren, Duquesne, Pa.

Application January 23, 1934, Serial No. 707,989

4 Claims. (Cl. 242—158)

This invention relates to a cable guiding device for hoisting drums, and particularly to those such as are commonly used on electric overhead cranes, although not limited thereto.

5 In the use of electric overhead cranes, one or more power driven cylindrical drums are employed to wind a cable, or cables, which are usually of steel, upon their outer surfaces in order to obtain the required hoisting effect. Ordinarily, the surface of the drum, or drums, is grooved so that the hoisting cables will wrap themselves thereon in a helical course. Under most circumstances a "side-pull" occurs as the object being lifted is not directly beneath the point of tangency of the cable on the drum, and the cable will therefore become taut at an angle with respect to the vertical. If the line of "side-pull" is normal to the axis of the drum, no difficulty occurs. However, if the "side-pull" 10 is parallel to the axis of the drum or has a parallel resultant, there is a tendency for the cable to leave the proper groove and wrap itself irregularly upon the drum.

It also frequently happens that slack occurs in 25 the cable when the load is released, and it springs out of the proper groove into an incorrect position either to the right or left. Such occurrences sometimes cause the cable to be wrapped in two or more layers at one position so that, due to the thickness of the mass, it binds against 30 adjacent crane parts, and the rope is damaged. It is not unusual that such overlaps of the cable are impossible to unwind without great difficulty and the operation of the crane is temporarily interrupted.

One object of the present invention is to provide a novel cable guiding device for hoisting drums which will function to guide the cable into or out of the "active" groove of the drum at a true tangent with respect to the axis thereof. That is to say, the cable will be fed into or 40 out of the groove which is "receiving", or "paying-off", at a ninety degree angle with respect to the axis of the drum, allowance being made, 45 of course, for the variance resulting from the helix of the groove.

Another object is to provide a novel apparatus of the class described which will properly direct the cable into and out of the "active" groove and will, in addition, resiliently maintain the same 50 therein at a position adjacent its tangent.

Still another object is to provide an apparatus of the class described which can be cheaply and easily installed on existing crane equipment, and one which will be entirely automatic in operation and require little if any attention.

These and further objects of the invention will be apparent after referring to the drawings, in 60 which:

Figure 1 is a plan showing part of the apparatus of the invention.

Figure 2 is an elevation disclosing the entire apparatus in operation.

Figure 3 is a sectional end view on the line 65 III—III of Figure 2.

Figure 4 is a sectional view on the line IV—IV of Figure 3.

Figure 5 is a sectional view on the line V—V of Figure 4.

Referring more particularly to the drawings, the letter A designates a crane trolley which carries a shaft B on which there is mounted a hoisting drum C driven through a large gear D which is likewise secured to the shaft B.

The drum C has attached thereto a cable F having on its other end a grab bucket G for scooping quantities of piled material. As long as the cable F is directly beneath the point of tangency of the cable on the drum, the efficiency of the hoisting drum is unimpaired. However, when the cable F occupies the position shown in dotted lines and indicated at X in Figure 2, the difficulties previously recited are experienced.

According to the teaching of the present invention, the hoisting drum C, having the usual helical grooves 2, is provided with a frame comprising a plurality of segments, as at 4, 5 and 6 and which, when taken together, completely encircle the periphery of the drum. One end of the segment 4 is provided with a flange 7, as is one end of the segment 6 provided with a flange 8, while both ends of the segment 5 are flanged, as at 9. The adjoining ends of the segments 4 and 6 are united in a hinge-joint 10, which is in the form of a hub provided with a central aperture 12. A hub 14 is integrally united to the segment 5 and provided with a central aperture 15. A pair of shafts 16 and 17 are suitably connected to the crane trolley A in close proximity to the shaft B and on opposite sides thereof, in such manner as to extend through the hubs 10 and 14, respectively.

A plurality of shoes 18 are each provided with a series of ribs 19 conforming substantially to the contour of the helical grooves 2 on the drum C, and two of the same carry a flange 20 extending at right angles with respect to the axis of the ribs 19. One of the shoes 18 is disposed with its flange 20 between the flange 7 of the segment 4 and one of the flanges 9 of the shoes 5, while the other of the shoes 18 is disposed with its flange 20 between the flange 8 of the segment 6 and the other flange 9 of the segment 5. The flanges 20 of the shoes 18 are held between the flanges of the various segments by means of bolts 21 and nuts 22, and permits their ribs 19 extending into the grooves 2 of the hoisting drum C.

The hinge-joint 10, formed by segments 4 and 6, provides a recess 24 for receiving a flange 25 on another of the shoes 18 and which extends in the same direction as the axis of the ribs 19. This shoe is suitably supported by having its flange 25 apertured at 26 in such manner as to permit the shaft 16 to extend therethrough.

The segment 4 is further provided with an extension 27 and a clamp 28 having a recess 29. 10 A guiding thimble 30 is disposed between the extension 27 and the clamp 28 and maintained in position in the recess 29 by means of bolts 31 and nuts 32. In its preferred construction, the thimble 30 is bell or funnel-shaped, and composed of a split and renewable hard-bronze casting which is so positioned as to have its aperture receive a tangent of the hoisting drum C, allowance being made, of course, for the slight variance resulting from the helical grooving of 15 the drum.

A pair of flanges 34 are integrally formed with the segment 4 and made to extend in a direction parallel to the axis of the drum. A pair of ears 35 are likewise integrally formed with the 25 segment 4 and provided with a pivot pin 36 to which one end of a shaft 37 is connected and made to occupy a position between the flanges 34. The other end of the shaft 37 is rounded, as at 38, and provided with a threaded extremity 39. A grooved pulley 40 is journaled on the rounded portion 38 of the shaft 37 and maintained in position by means of a nut 41 and washer 42.

The segment 4 has an aperture 43, and a similar aperture 44 is provided in the shaft 37 and in alignment therewith. A headed bolt 45 is made to extend through the aperture 43 in the segment 4 and the aperture 44 in the shaft 37, and provided with a threaded end 46. A 40 spring 48 is positioned over the threaded end 46 of the bolt 45 and between washers 47, a nut 49 being provided for establishing a resilient and adjustable influence on the shaft 37 on which the grooved pulley 40 is mounted.

45 In installation, the segments 4, 5 and 6 carrying the shoes 18 are assembled with the ribs of the latter occupying a number of the helical grooves 2 in the drum C. The cable F on the drum is threaded under the pulley 40 and 50 through the aperture of the guiding bell 30. As the winding operation is commenced, the cable will travel through the bell 30 and onto the helical grooves 2 of the drum at an exact tangent, and will be made to stay in said groove by 55 means of the grooved pulley 40 which is resiliently maintained in contact therewith by means of the adjusting nut 49 through the tension spring 48. It will thus be seen that due to the positioning of the ribs 19, of the shoes 18, in 60 the grooves 2 of the drum, the frame composed of the segments 4, 5 and 6 will be made to travel on the shafts 16 and 17 along the axis of the drum, and in such manner as to position the guiding bell 30 and the groove pulley 40 in 65 working relationship with respect to the "active" groove of the drum, or that which is either "paying off" or "receiving" the cable, and thus obviate all of the difficulties previously referred to.

70 While I have shown and described one specific embodiment of my invention, it will be understood that I do not wish to be limited exactly

thereto, since various modifications may be made without departing from the scope of my invention, as defined in the following claims.

I claim:

1. A cable guiding device for hoisting drums comprising a slidable frame adapted to encircle at least a substantial portion of the circumference of said drum, at least one shoe connected to said frame and adapted to seat in at least one of the grooves in said drum, means for guiding the cable into the active groove in said drum, a shaft pivoted to said frame with its axis substantially parallel to the axis of said drum, a pulley on said shaft, and resilient means for influencing said shaft in such manner as to cause said pulley to be positioned closely adjacent said active groove and to make contact with said cable. 80

2. A cable guiding device for hoisting drums comprising a slidable frame adapted to encircle at least a substantial portion of the circumference of said drum, at least one shoe connected to said frame and adapted to seat in at least one of the grooves in said drum, means for guiding the cable into the active groove in said drum, a shaft pivoted to said frame with its axis substantially parallel to the axis of said drum, a pulley on said shaft, resilient means for influencing said shaft in such manner as to cause said pulley to be positioned closely adjacent said active groove and to make contact with said cable, said resilient means comprising a bolt extending through a portion of said frame and through said pivoted shaft, a spring encircling said bolt, and an adjusting nut for compressing 95 said spring. 100

3. A cable guiding device for hoisting drums comprising a slidable frame adapted to encircle at least a substantial portion of the circumference of said drum, at least one shoe connected to said frame and adapted to seat in at least one of the grooves in said drum, means for guiding the cable into the active groove in said drum, a shaft pivoted to said frame with its axis substantially parallel to the axis of said drum, a pulley on said shaft, and resilient means for influencing said shaft in such manner as to cause said pulley to be positioned closely adjacent said active groove and to make contact with said cable, said guiding means including a bell having an aperture aligned with a tangent of said drum. 115

4. A cable guiding device for hoisting drums comprising a slidable frame adapted for movement along the axis of said drum, at least one shoe connected to said frame and adapted to seat in at least one of the grooves in said drum, an extension on said frame, a clamp for said extension, a guiding bell disposed between said extension and said clamp and having an aperture aligned with a tangent of the active groove of said hoisting drum, in combination with a shaft pivoted to said frame with its axis substantially parallel to the axis of said drum, a pulley on said shaft, a bolt extending through said frame and said shaft, a spring on said bolt, and an adjusting nut for resiliently influencing said pulley against the active groove of said hoisting drum in such manner as to maintain the cable in said groove as it is being fed into and out 130 of said guiding bell. 140

BROR A. E. ROSENQUIST.
